PHOTOGRAPHIC MATERIAL

Otto Vierling, Dresden, Germany; vested in the
Alien Property CustodianApplication January 4, 1940, Serial No. 312,345
In Germany December 31, 1935

3 Claims. (Cl. 95—7)

The invention relates to improvements in photographic material.

An object of the invention is to provide a photographic material permitting a picture to be produced thereon from a negative and having the distinctive characteristics that this picture may be caused to disappear again upon irradiation of the material with a light of certain wave length.

A process of producing pictures on phototropic material is described in the application Serial No. 118,372, for which Letters Patent No. 2,186,942 was issued on January 16, 1940, and of which the present application is a continuation-in-part.

A further object of the present invention is to provide a phototropic material of the character described in a form in which it can readily be used for the production of the picture as well as for the disappearance of the same.

It is also an object of the invention to provide an article of manufacture in which this material is supplied in predetermined shape in the form of a sheet ready to be positioned in the path of a light projected through a negative onto the material.

It had been proposed heretofore to make use of the phototropic qualities of fulgides for the purposes set forth herein, but in these prior methods of producing pictures, the fulgides were used in the form of a solution of the fulgide in acetone, collodion or in the form of a solution of other solvents. In these prior processes the fulgides were used as dyestuffs combined in their solutions with different catalysts also preferably of liquid consistency. Catalysts of this type, for instance, iodium or nitrobenzol, had been necessary in order to accelerate the bleaching out process just as the solvents for the fulgides had been believed to be necessary for the change of color of the fulgides in producing the picture.

As contrasted with these prior methods of utilizing the phototropic material in solution and in combination with catalysts of liquid consistency, the present invention makes use of the fulgides or other phototropic substances in the form of solids.

With these and numerous other objects in view, the invention is described under reference to the accompanying drawing, wherein Figs. 1 to 5 show perspective various embodiments of articles of manufacture constituting the subject matter of the present invention.

In the embodiment illustrated in Fig. 1, the new article of manufacture comprises a layer or sheet of a phototropic substance of sufficiently

solid consistency by itself to permit its use in photographic equipment, as for instance, in copying apparatus, enlargers and the like. The layer 1 may be produced from the phototropic substance by fusion and subsequent hardening of the phototropic substance, or by compressing the substance into the form of a web or sheet or the like. Phototropic substances which can be used for this purpose are, for instance, the fulgides, as triphenyl-fulgide— $C_{24}H_{16}O_3$, or diphenylortho-phenyl-fulgide. The normal color of these compounds is orange-red or red, and when exposed to blue light or blue-greenish light, this color changes into brownish-black.

Similar results are obtained when some of the compounds of the group of hydrazones are employed.

While in the prior methods of producing photo-prints by means of fulgides, the solutions of the fulgides were poured upon a carrier and were subsequently sensitized by additions of phenetol or nitrobenzol, the present invention provides the fulgides in solid form ready to be used without requiring their being dissolved. In this manner the production of these articles of manufacture is greatly facilitated, as well as the method of using the articles.

In the embodiment illustrated in Fig. 2, the phototropic material in the form of a layer 1 is supported by a base 2. The phototropic material may again for instance be a fulgide, while the base 2 may consist of paper, ground glass or the like. The layer 1 of phototropic material is permanently applied to the base by pressure owing to its inherent adhesiveness. The assembly of base and phototropic layer then constitutes the article of manufacture which is the subject of the present invention.

In the embodiment illustrated in Fig. 3, the layer 1 of phototropic material, as for instance, fulgide, is associated with a base 2 by means of a binder 3 interposed between the base and the layer. The base again may be produced from paper, ground glass, fabric or the like, and the binder may be a suitable, transparent, adhesive material of which many are known in the art—a gelatine or the like.

This combination of a layer of phototropic material free of catalysts, solvents or the like, a binder and a base, constitutes a new article of manufacture in flat solid form which is particularly suitable for use in photographic printing devices, enlargers and the like. Positives produced thereon through a suitable negative may again be caused to disappear rapidly when it is

exposed to radiation with light, and particularly with light of relatively great wave length.

It has also been found that this article of manufacture as well as the other embodiments described and illustrated in the present specification may be reutilized numberless times without their effect being in any way weakened by the repeated radiations by the light which produces the pictures and by the light which causes the pictures to disappear.

The embodiment illustrated in Fig. 4 again consists of a flat sheet-like body 5 in which finely divided phototropic material 6, as for instance fulgides, is commingled with a binder material 7 adapted to harden, so that the compound article 5 constitutes a single homogeneous layer consisting of the carrier 7 in which the phototropic material 6 is uniformly dispersed. The binder or carrier 7 may be a substance which can readily be reduced to liquid consistency, but which will remain hard at normal temperature. Gelatine, for instance, may constitute the material in which the finely divided phototropic substance may be dispersed in this manner. In this form also the new article of manufacture will be in condition for use without requiring the addition of solvents or catalysts, and the production of the pictures as well as their disappearance is accelerated owing to the use of the phototropic material in uncontaminated condition, while the manipulations required in the use of the article are greatly simplified.

In the embodiment illustrated in Fig. 5, the layer 1 of phototropic material may be positioned between two protective plates 8 and 10, as for instance, glass plates or plates of other transparent material. The layer 1 produced by compression or fusion and subsequent hardening may be applied to the protective plates 8 and 10 either by its own inherent adhesiveness, or it may be united with the protective plates of transparent material by a transparent binder. It is obvious, furthermore, that instead of utilizing a layer of the type illustrated in Fig. 1 between two transparent protective plates, a layer of the type illustrated in Fig. 4, may be used in which the phototropic material is finely dispersed within a trans-

parent binder adapted to harden at normal temperatures and having sufficient inherent adhesiveness to unite this layer with the protective plates 8 and 10.

5 In all of the embodiments illustrated, it is the phototropic material as such which serves to receive the pictures and which is adapted to permit the pictures to be removed therefrom by radiation. Owing to this utilization of the phototropic material in the form of a coherent solid layer with or without any support, the production of the new article of manufacture also is less costly than the production of a phototropic material by solution in a suitable solvent and 10 the addition of catalysts which render this solution suitable for receiving the pictures. The catalysts previously used in association with fulgides were photoactive substances, and the fulgides in themselves merely served as dyestuffs for these catalysts to render the effect more noticeable. As contrasted with these prior materials, in the present invention it is the fulgide itself (or some other phototropic material as a compound of the group of hydrazones) in solid form and 15 free from catalysts which accelerates the action and the article is free from ingredients, as solvents, which would have a tendency to retard the action.

The article can be produced in all suitable sizes, and placed at the disposal of the public just as plates or films for ordinary photographic material.

I claim:

1. As a new article of manufacture, a solid coherent layer of pure fulgides in the form of a flat solid sheet and a base on which said layer is firmly supported.

2. As a new article of manufacture, a layer of pure fulgides in the form of a solid coherent sheet firmly united with a supporting transparent base of flat sheet-like form.

3. As a new article of manufacture, a layer of pure fulgide, free of catalysts and solvents, in the form of a solid coherent sheet, and a pair of 45 transparent protector plates below and above said layer and to which said layer is firmly united.

OTTO VIERLING.
